UNITED STATES PATENT OFFICE.

FREDERICK A. HART, OF NEWARK, NEW JERSEY, ASSIGNOR TO UNDERWOOD COMPUTING MACHINE COMPANY, OF NEW YORK, N. Y., A CORPORATION OF NEW YORK.

TYPEWRITING-MACHINE.

1,357,557.

Specification of Letters Patent. Patented Nov. 2, 1920.

Application filed April 6, 1916. Serial No. 89,254.

To all whom it may concern:

Be it known that I, FREDERICK A. HART, a citizen of the United States, residing in Newark, in the county of Essex and State of New Jersey, have invented certain new and useful Improvements in Typewriting-Machines, of which the following is a specification.

This invention relates to means forming part of a typewriting machine for automatically pointing off or spacing between figures, as between dollars and cents and between hundreds and thousands, etc., in writing numbers, whereby the operator is relieved of the necessity of printing commas or periods or operating a space key to effect such spacing.

In my co-pending applications No. 79,969, filed February 23, 1916, now Patent No. 1,282,823, granted October 29, 1918, and No. 88,982, filed April 5, 1916, now Patent No. 1,302,159, granted April 29, 1919, I have shown spacing means by which the spacing or pointing off between digits is controlled by the carriage escapement mechanism, said mechanism comprising an escapement dog which has a variable throw to vary the letter-feed movement of the carriage. The throw of said dog is controlled by a stop device, which is operable to vary the stop position of said dog.

In said Patent No. 1,302,159 said stop device is controlled from the totalizer of the computing mechanism, said totalizer being adjustable on the carriage to determine the computing zone and having means to automatically operate said stop device at a predetermined position of the carriage in the computing zone, to effect double-space letter-feed movements of the carriage and thereby space between the digits of the numbers being written at the desired denominational positions. Said Patent No. 1,302,159 further discloses case-shifting mechanism, a non-computing key for silencing the computing mechanism, and means for automatically silencing the said double-spacing means when either the non-computing key or a case-shift key is actuated.

An object of the present invention is to provide an improved form of mechanism for actuating the stop device for the escapement dog which controls the double-space movements of the carriage, said mechanism

being arranged to control the stop device from a convenient point on the carriage, through connections which are simple and direct. Preferably there is provided on the carriage, in the rear of the platen, an actuator for setting the stop device to permit a double-space movement of the carriage, which actuator may be adjustably mounted on a rack on the carriage adjacent to the usual tabulator rack. Said actuator may be positioned to intercept tappets on a swinging bail mounted on the machine frame to thereby automatically actuate said bail during the letter-feed travel of the carriage, and through suitable connections between said bail and the stop device which controls the escapement dog, position said stop device to cause double letter-space movements of the carriage at points at which it is desired to space between digits of the number being written. The said actuator for controlling the double-spacing means, may consist of a plate adjustable through letter-space intervals along its supporting rack to any desired position lengthwise of the platen, which position may be determined by that of a set tabulator stop.

The invention may be used in connection with a machine in which the tabulator mechanism comprises a rack having stops at letter-space intervals, which stops may be selectively set to operative position. A scale may be provided adjacent the rack carrying said actuator or actuators, so that the latter may be readily set to positions corresponding to those of the set tabulator stops. The computing mechanism may be similar to that disclosed in the Patent No. 1,302,159, above referred to, and may comprise a "non-add" or disconnect key to silence the computing mechanism, said key also operating means to silence the double-spacing mechanism.

As shown in the present application, the non-add or disconnect key operates through suitable connections to swing a frame pivotally mounted on the machine frame and carrying said tappeted bail, to swing the latter out of the path of the actuators on the carriage and thereby prevent the double-spacing operations. The platen-shifting frame by which the platen is shifted to upper-case position may also have connection with said swinging frame for silencing

the double-spacing mechanism when a shift-key is operated.

The automatic double-spacing mechanism may in some instances be used independently of the computing mechanism, or on typewriting machines without computing mechanism.

Other features and advantages will hereinafter appear.

10 In the accompanying drawings,

Figure 1 is a part-sectional side elevation of a combined typewriting and computing machine constructed in accordance with the principles of the present invention.

15 Fig. 2 is a fragmentary front perspective view, showing particularly the escapement mechanism, the tappeted bail controlling the stop device for the escapement dog, and the actuator for said bail.

20 Fig. 3 is a front view of the escapement mechanism, with the parts in their normal position of rest, in which the escapement wheel is held by the loose dog.

25 Fig. 4 is a similar view, but with the escapement wheel held by the fixed dog, the loose dog being positioned for normal letter feeding by the variable stop device.

30 Fig. 5 is a view similar to Fig. 4, except that the stop device is positioned to permit a double-space throw of the loose dog.

Fig. 6 is a schematic view of the invention.

The typewriting machine which, in most respects, is the same as the usual commercial Underwood machine, comprises a carriage

35 mounted to travel on front and rear guide rails 11 and 12, the carriage being propelled by a spring motor 13 connected through a band 14 to the carriage. A roller platen 15 has an axle 16 journaled in the platen frame

40 17 shiftable up and down on the carriage to bring the platen to upper and lower-case positions. A shift-key 18 fulcrumed as usual in the Underwood typewriting machine at 19 has an arm 20 extending up-

45 wardly behind the platen shift frame 21 fulcrumed at 22 and comprising a shift rail 23 on which runs a roller 24 on the platen frame. When the shift-key is depressed, the shift-frame 21 is operated to shift the platen to upper-case position.

50 Type-bars 25 carrying upper and lower case-types 26, 27, are mounted on a fulcrum rod 28 to swing upwardly and rearwardly, to cause the types to strike against the front face of the platen. Alphabet keys 29 and numeral keys 30 are fulcrumed at 19 and are connected through bell-crank 31 to their respective type-bars for actuating the latter.

55 The escapement mechanism which controls the letter-feed movements of the carriage, comprises an escapement wheel 32 having a one-way driving connection through dogs 33 with an escapement pinion 34, which runs in mesh with a carriage rack 35, the latter carried by arms 36 pivotally

mounted on the carriage to permit the rack 35 to be swung off the escapement pinion. The escapement wheel 32 has a step-by-step movement controlled by a fixed dog 37 fixed on a dog-rocker 38 and a loose dog 39 pivoted at 40 to the dog-rocker. The latter is actuated at each type-stroke by means of a universal bar 41 in the path of shoulders 42 on the type-bars, so that when a type-bar is moved to printing position, the universal bar 41 swings the upper end of the dog-rocker rearwardly. The universal bar is returned by a spring 43 when the type-bar returns to normal position. Figs. 2 and 3 show the parts in their normal position of rest, wherein the escapement wheel is held by the loose dog 39 against which bears one of the teeth 44 of the escapement wheel.

When a type-bar is operated and the upper end of the dog-rocker 38 is swung rearwardly, as above noted, the fixed dog 37 is brought into the path of said tooth and holds the escapement wheel while the loose dog is moved rearwardly out of engagement with said tooth and thereby released to its spring 45, which swings the dog to the left until arrested by a stop 46 (Fig. 4) in the path of a pin 46' on the dog.

As the actuated type-bar returns and permits the universal bar to be returned by its spring 43, the spring 45 returns the dog-rocker 38, thereby swinging the pivoted dog 39 forward in front of the next tooth of the escapement wheel, and also swings the fixed dog 37 forward out of the path of the wheel, permitting the latter, under the influence of the carriage spring, to be rotated the distance of one tooth, that is, a normal letter-space distance. The pivoted dog, during this movement of the wheel, is swung to the right until arrested by a stop on the dog-rocker.

Tabulator mechanism may be provided comprising tabulator keys 47 connected to levers 48 pivoted at 49 to operate decimal-tabulator stops 50, said stops being in the form of vertical bars or plungers mounted for vertical movement in a tabulator frame 51. Column-stops 52 are mounted at letter-space intervals on a rack 53 on the carriage. The stops 52, as shown, are mounted for a limited vertical movement in the rack bar 53, so that any desired stop may be set or moved downward in the rack to operative position, namely, to a position to be intercepted by any denomination stop 50 which has been projected by depressing its key 47. The stops 52 may be selectively set as desired by any suitable form of key-actuated selective stop-setting mechanism, such as shown, for example, in the patent to Doane No. 1,157,683.

When any of the plunger stops 50 is actuated, it operates through a universal bar 54 pivoted at 55 and connected through a link 56

56 to a lever 57 carrying a roller 58, to lift the rack bar 35. The carriage is thus released from the control of the escapement mechanism and permitted to run forward 5 until arrested by a set stop 52 engaging the projected stop 50, thereby positioning the carriage at the column and the denominational position in the column, determined by the operative stops 52 and 50, respectively.

10 The computing mechanism may comprise one or more totalizers 59, each connected to travel with the carriage by means of a latch 60 engaging a rack bar 61 on the carriage, whereby the totalizer may be adjusted 15 through letter-space intervals to any desired position lengthwise of the carriage. The totalizer is provided with guide rollers 59^a and 59^b to run on a rail 59^c on the machine frame. The totalizer comprises dial 20 wheels 62 and computing wheels 63 actuated by the computing mechanism mounted on the machine frame, said mechanism comprising a master wheel 64 which, during the writing of the several digits of a number, 25 is brought into operative relation with the computing wheels 63 successively and operates said wheels to run up on the dial wheels the number being written.

The operating means between the numeral 30 keys 30 and the computing wheels comprises differentiators 65 on the numeral-key-levers, each differentiator being in the form of a plate with a cam slot 66. A rod 67 extends across the machine in position to be actuated 35 by any one of said differentiators, said rod being carried by swinging arms 68 on a shaft 69. When any numeral key is depressed, the cam slot 66 of the corresponding differentiator is moved downward over 40 the rod 67, so that the latter is cammed forward. The upper ends of the slots are in stepped relation, the slots being so formed that the extent of movement imparted to the rod 67 will correspond with the value of the 45 digit represented by the actuated key, so that the computing mechanism will be operated a corresponding extent.

The connections between the differentiator and the computing wheels are as follows:

50 A pin 70 connected to an arm 68 engages a notch in a floating lever 71 pivoted at 72 to a lever 73 fulcrumed at 69. Said lever 71 is normally held against the pin 70 by a spring 74, so that the forward movement of the rod 55 67 when a key is depressed, operates through the pin 70 and lever 71 to swing lever 73 about its fulcrum, and thereby move downwardly a link 75 connected to a rock arm 76 on a shaft 77. A second arm 78 on the shaft 60 77 is connected through a link 79 to a rack 80, which drives a pinion 81 fixed to a shaft 82. A gear wheel 83 which rotates with the pinion 81, is shiftable by means of an add or subtract key (not shown) into direct 65 driving relation either to a pinion 84 or a pinion 85, the latter being connected to drive the master wheel 64. The pinion 84 may be at all times in driving relation with the pinion 85. In adding, the gear wheel 83 drives the master wheel directly through the pinion 85 in one direction, and in subtracting, the gear wheel 83 operates through the pinions 84 and 85 to drive the master wheel in the opposite direction. The construction and operation of the computing mechanism 70 thus far described may be substantially like that disclosed in the application of Henry L. Pitman, No. 24,390, filed April 28, 1915, now Patent No. 1,308,506, dated July 1, 1919.

75 Before a computing operation, the totalizer may be adjusted to a position corresponding to that of the set tabulator stop 52. The numeral keys may be operated in the usual manner to print any desired number. As each numeral key is depressed, it 80 operates through the connections above described to rotate the master wheel 64 through a distance corresponding to the digit of the particular key operated. The master wheel drives the particular computing wheel 63 85 and dial wheel 62 which are at the time being in register therewith, to run up on the totalizer the corresponding number. Such operation takes place during the depression of the numeral key. As said key is returned, 90 the escapement mechanism permits the carriage to advance a letter-space distance, thereby bringing the master wheel into register with the next succeeding computing wheel 63.

95 In order to automatically point off or space at the decimal positions and between the digits in the hundreds and thousands positions, etc., mechanism is provided for automatically effecting a double-space letter-feed movement of the carriage when such positions are reached. For this purpose, the throw of the loose dog 39 of the escapement mechanism is variably controlled by a shiftable stop device 86 in the form of a lever 100 pivoted on a stud 87 on the escapement frame, the lever being held against endwise displacement on the stud by nuts 88. Said stop device 86 comprises the stop 46 heretofore referred to, which normally limits the 105 throw of the dog 39, and a second stop 89 which may be brought into position to control said dog for a double-space movement. The stop device 86 is actuated or set for causing a double space movement, by means 110 of an actuator 99 on the carriage, which depresses tappets 90 on a bail 91 pivoted at 92 to a swinging frame 93 mounted by pivots 94 on the tabulator frame 51. The bail 91 comprises a forwardly-extending arm 115 95 connected through a link 96 to a rearwardly extending arm 86^a of the stop device 86. A spring 97 is connected to the arm 95 to pull downwardly thereon and thereby normally hold the stop device 86 to the Fig. 120

125 95

130

3 position, in which the stop 46 is operative, the movement of the stop device by said spring being limited by a projection 98 thereon striking the escapement frame. The 5 spring 97 holds the tappets or cams 90 in the path of the actuator 99 which may be in the form of a plate removably mounted on a rack bar 100 extending lengthwise of the carriage, said plate being adjustable to any 10 desired letter-space position along the rack.

The actuator 99 is adjusted with respect to the set tabulator stop 52 or the position of the totalizer which determines the computing zone, so that the double-space movements of the carriage will take place at the 15 desired denominational positions. The rack bar 100 may be connected to the tabulator rack bar 53 by means of brackets 101. A graduated scale 102, which may be conveniently mounted on the rack bar 53, facilitates the quick and accurate setting of the actuator 99 to correspond with the set tabulator stop and the position of the totalizer.

To explain the operation of the double-spacing mechanism, let it be assumed that the totalizer is in the computing zone at the ten-thousands position. If now a numeral key is operated to print a digit in such position, the carriage will, upon the return of 20 the key, advance a single letter-space distance, as usual; the escapement wheel, during such advance of the carriage, operating to swing the loose dog from the Fig. 4 position to the Fig. 3 position. During this 25 movement of the carriage, however, a tappet 90 strikes the actuator 99, and the bail 91 is swung downwardly, and through the link 93 swings the stop device 86 from the Fig. 4 position to the Fig. 5 position. The 30 carriage is now at the thousands position, so that the next numeral key struck prints in the thousands place. During this printing operation, the dog-rocker 38 is swung rearwardly, as usual, to release the loose dog, 35 which is now permitted to swing to the Fig. 5 position, owing to the position of the stop device 86, so that when the dog-rocker is returned, the loose dog permits the escapement wheel to advance a distance of two 40 teeth, thereby effecting a double letter-space movement of the carriage. Thus, the next operated numeral key will print in the hundreds place, a double letter-space in advance of the preceding digit. The double-space 45 movement of the carriage moves the plate 99 off the tappet 90, so that the stop device 86 is reset to the Fig. 3 position, whereby the carriage will only be permitted a single letter-space movement at the next printing operation. The succeeding tappet will operate at the proper time to space at the 50 decimal position.

A "non-add" or silencing key 103 for the computing mechanism is connected through 55 a link 104 to an arm 105 of a lever 106 piv-

oted at 107. Said lever comprises an arm 108 having a lug 108^a to engage the lever 71, so that when the key 103 is thrown forward, the lever 71 is thereby depressed to release it from the pin 70, so that the differentiators 70 on the numeral keys will swing the bar 67 idly when the numeral keys are operated, without affecting the computing mechanism.

In order to silence the double-spacing mechanism when the key 103 is operated, the 75 swinging frame 93, which carries the tappet bail 91, is connected through a link 110 with an arm 111 of the lever 106, so that as the non-add or disconnect key 103 is moved forwardly the link 110 is moved rearwardly 80 and swings the frame 93 to carry the tappet bail 91 forwardly and move the tappets 90 out of the path of the actuator 99.

Means for silencing the double-spacing mechanism when a platen shift key is operated, comprises a link 112 connecting the upper end of the lever 106 to a pin 113 on the shift frame 21. When a shift key 18 is depressed, the movement of the shift frame 21 is transmitted through the pin 113 and 90 link 112 to the lever 106, the movement of the lever operating as before described to swing the tappet bail free of the actuator 99, thus preventing an operation of the stop device 86 which would effect a double-space 95 letter-feed movement of the carriage.

The slot-and-pin connection shown between the link 112 and the platen shift frame, permits the key 103 to be operated without affecting said shift frame. 100

A slot-and-pin connection 114 between the key 103 and the link 104 likewise permits the platen-shifting operation to take place without moving the key 103. The case-shift key 18 operates through the mechanism 105 described to silence the computing mechanism as well as the double-spacing mechanism. It will be noted that the lever 106 serves as a means for silencing both the computing mechanism and the double-spacing mechanism, and that said lever may be actuated by either the platen shift key or the "non-add" key without affecting the other.

Variations may be resorted to within the 115 scope of the invention, and portions of the improvements may be used without others.

Having thus described my invention, I claim:

1. In a typewriting machine, the combination with a carriage and propelling means therefor, of escapement mechanism permitting letter-feed movements of the carriage, tabulator mechanism comprising a series of tabulator stops selectively settable to arrest the carriage at a selected position, double-spacing mechanism for automatically effecting a double-space letter-feed movement of the carriage, and an actuator for setting said double-spacing mech- 120
125
130

anism for operation, said actuator adjustable to a predetermined position relative to the set tabulator stop, to thereby determine the position in which the double-spacing mechanism is brought into activity.

2. In a typewriting machine, the combination

with a carriage and propelling means therefor, of escapement mechanism controlling the letter-feed movements of the carriage, character keys for printing, said keys controlling the escapement mechanism, tabulator mechanism comprising a rack bar mounted on the carriage and having a series of individually-settable stops, said tabulator

10 mechanism comprising a key, a counter-stop, and means operated by said key to project the counter-stop into the path of a set stop and to release the carriage from the control of the escapement mechanism, to permit the carriage to run forward to a position determined by the set stop, and mechanism for effecting a double letter-space movement of the carriage by the operation of a character key when the carriage has reached a predetermined position during its letter-feed travel, said double-spacing mechanism comprising an actuator, and a rack on the carriage on which said actuator is mounted for adjustment through letter-space intervals to 20 a position lengthwise of the carriage corresponding to the position of the set tabulator stop, said double-spacing mechanism comprising means on the machine frame in the path of said actuator and operated by the latter, to cause said double-space movement of the carriage at a position corresponding to that of the set tabulator stop.

3. In a typewriter, in combination, a letter-spacing carriage, an escapement mechanism therefor comprising a fixed dog and a loose dog, a variably-settable stop-device to selectively determine the extent of throw of said loose dog, said stop-device being normally set to cause said escapement to effect 40 single letter-spacing movements of said carriage, a tappet on said carriage, and means, rendered effective thereby on movement of said carriage into a letter-space position determined by the location of said tappet, for 45 varying the setting of said stop-device, so as to permit an amplified throw of said loose dog and thereby cause said escapement to effect a double letter-spacing movement of said carriage at its next letter-spacing movement.

4. In a typewriter, in combination, a letter-spacing carriage, an escapement mechanism therefor comprising a fixed dog and a loose-dog, a variably-settable stop-device 60 to selectively determine the extent of throw of said loose dog, said stop-device being normally set to cause said escapement to effect single letter-spacing movements of said carriage, a tappet on said carriage, and, 65 means, rendered effective thereby on move-

ment of said carriage into a letter-space position determined by the location of said tappet, for varying the setting of said stop-device, so as to permit an amplified throw of said loose dog and thereby cause said 70 escapement to effect a double letter-spacing movement of said carriage at its next letter-spacing movement, the carriage-controlled setting means being freed from control by said tappet during such double letter-spacing movement of said carriage, so as to permit said stop-device to be restored to its setting determinative of single letter-spacing movements of said carriage.

5. In a typewriting machine, the combination with a letter-feeding carriage and an escapement mechanism therefor, of a fixed dog and a loose dog for feeding said carriage, a stop adapted to variably limit the throw of said loose dog, tabulating mechanism for said carriage, including a mounting therefor, a bail pivotally mounted on said mounting, a connection from said bail to said dog, and a tappet on said carriage adapted to selectively move said bail to vary 85 the throw of said loose dog.

6. In a typewriting machine, the combination with a letter-feeding carriage and an escapement therefor, including a fixed and a loose dog, of a stop for varying the throw 90 of said loose dog, a bail comprising a plurality of tappets, a connection from said bail to said stop, and a lug on said carriage adapted to coöperate with said tappets to vary the throw of said loose dog. 100

7. In a typewriting machine, the combination with a letter-feeding carriage and an escapement mechanism therefor, including a fixed and a loose dog, of a stop for varying the throw of said loose dog, a bail adjustable relatively to said carriage independently of the escapement mechanism and comprising a plurality of tappets, a connection from said bail to said stop, and a plurality of lugs on said carriage settable to effective or ineffective position, and when effective adapted to control said stop. 105

8. In a typewriting machine, the combination with a letter-feeding carriage and escapement devices therefor, including a fixed dog and a loose dog, of a stop adjustable to vary the throw of said loose dog, a bail adjacent the travel of said typewriter carriage, a connection from said bail to said stop, a rack bar carrying a plurality of tabulating stops forming a part of a tabulating device, tappets on said bail, and a second rack bar carrying blades adapted to be set into effective position to actuate said bail by said tappets at times coöordinated with 115 said tabulating stops.

9. In a typewriting machine, the combination with a letter-feeding typewriter carriage and escapement devices therefor, including a fixed dog and a loose dog, of a 120

- stop adjustable to vary the throw of said loose dog, a bail adjacent the travel of said typewriter carriage, a connection from said bail to said stop, a rack bar carrying a set-
5 table stop for substantially every letter-space in the feed of said typewriter carriage, tappets on said bail, a second rack bar, and blades in said second rack bar normally in ineffective position, but adapted to be set
10 to position in effective alignment with any effective tabulating stop to actuate said bail by said tappets.
10. In a typewriting machine, the combination with a letter-feeding typewriter carriage and escapement devices therefor, including a wheel and a fixed and a loose dog coöperating with said wheel, of a stop for varying the idle throw of said loose dog, a bail adjacent the travel of said typewriter carriage and connected to said stop, means for positioning said bail independently of the adjustment of the escapement devices, and means mounted on the typewriter carriage for actuating said bail.
15 11. In a typewriting machine, the combination with a letter-feeding typewriter carriage and escapement devices therefor, including a wheel and a fixed and a loose dog coöperating with said wheel, of a stop for varying the idle throw of said loose dog, a bail adjacent the travel of said typewriter carriage and connected to said stop, means for positioning said bail independently of the adjustment of the escapement devices, two rack bars on said typewriter carriage, 35
20 and blades mounted in each rack bar at letter-space intervals therein, and normally ineffective, tabulating stops for coöperating with any effective blade in one rack bar, and lugs on said bail adapted to coöperate with any 40 effective blade on the other rack bar, the adjustments being such that aligned blades are effective at the same letter-spaces on the escapement mechanism and on the tabulating mechanism.
25 12. In a typewriting machine, the combination with a letter-feeding typewriter carriage and escapement devices therefor, including a wheel and a fixed and a loose dog coöperating with said wheel, of a stop for varying the idle throw of said loose dog, a bail adjacent the travel of said typewriter carriage and connected to said stop, bail-actuating means mounted on the typewriter carriage, and means for positioning the bail 50 in or out of the path of said actuating means.
